UNITED STATES PATENT OFFICE.

THOMAS K. STANLEY, OF ST. LOUIS, MISSOURI.

DESIGN FOR A BOLSTER.

SPECIFICATION forming part of Design No. 31,652, dated October 10, 1899.

Application filed September 2, 1899. Serial No. 729,391. Term of patent 14 years.

To all whom it may concern:

Be it known that I, THOMAS K. STANLEY, a citizen of the United States, residing at the city of St. Louis, in the State of Missouri, have 5 invented and produced a new and original Design for Bolsters, of which the following is a specification, reference being had to the accompanying drawings, forming part thereof.

Figure 1 is a perspective view of a bolster, 10 showing my new design; and Fig. 2 is an end view of the bolster.

As shown in the drawings, the leading or material features of my design consist of a lace-covered bolster or roll 1, having an ornamental marginal border 2 surrounding the same adjacent to the ends of said bolster, a central figure of ornamental design 3, and the opposite ends of the bolster provided with lace covers having a marginal border 4 and a

central figure 5. The whole when made up in 20 the form as shown in the drawings and when used in connection with a lace cover or spread, as patented to me on the 30th day of May, 1899, No. 30,930, will give the bed upon which it is placed a very neat and attractive appearance.

Having described my invention, what I claim as new, and desire to secure by Letters Patent, is—

The design for a bolster, as herein shown 30 and described.

In testimony whereof I affix my signature in presence of two witnesses.

THOMAS K. STANLEY.

Witnesses:

ALFRED A. MATHEY,
C. F. KELLER.
